UNITED STATES PATENT OFFICE.

JOSIAH C. GOODING, OF COVINGTON, INDIANA.

DESIGN FOR A DESK AND SEAT.

SPECIFICATION forming part of Design No. 23,248, dated May 1, 1894.

Application filed March 27, 1894. Serial No. 505,342. Term of patent 14 years.

To all whom it may concern:

Be it known that I, JOSIAH C. GOODING, a citizen of the United States, residing at Covington, in the county of Fountain and State 5 of Indiana, have invented and produced a new and original Design for a Desk and Seat, of which the following is a specification.

The leading feature of my design consists in the lines and curves which make up the 10 general contour and configuration of the side pieces or frame-work, together with the top of the desk, and the seat and back thereof, and also in the lines of intersection or joinder of these severally recited parts.

15 In the accompanying drawings: Figure 1 is a view in perspective of a school desk and seat embodying my design. Fig. 2 is a side view; and Fig. 3 is a top or plan view thereof.

In the drawings only one of the side 20 pieces of the desk appears in any one of the figures, and the same is represented as a whole by the numeral 1. When viewed from the side, as in Fig. 2, the said side piece is presented in a single piece and its general 25 contour consists of a thickened or bar-like portion which begins at the lower end, where it rests upon the floor, with a flattened extremity 2, thence it bends or curves inwardly at 3 and gradually extends upward and outward to the point 4 when it changes from a 30 curve to an approximately straight portion 5 still continuing upward and slightly outward. Reaching the point 6 the same reverse direction and again turns inward at a slight upward 35 inclination from a horizontal line, as shown at 7, and extends across for a suitable distance until it reaches the point 8 whence it descends downwardly again at 9 at an inclination, and when reaching about half way 40 down it assumes the horizontal at 10, and finally curves inwardly at 11, and again outwardly at 12, where it terminates in a horizontal flattened extremity 13, in substantially the same horizontal plane as the flattened

portion 2. Intersecting the parts above described, at the points 14, 15, is a horizontal continuation 17 which since the whole design of the side piece is stamped from sheet metal will present an integral part. In my design it will also be observed that within the space 45 18 between the rising and descending portions of the side piece is located an ornamental rosette 19 which intersects such portions at the points 20; and besides this there are a larger ornamental rosette 21 and several intersecting scrolls 22, 23, 24 and 25. The receptacle 26 of the desk is located at the top of the side piece and is bounded by the lines 27, 28. The top or lid 29 of the desk is a planed flat surface and assumes the slightly 50 inclined position of the part marked 7 of the said hereinbefore described side piece. When viewed at the top, as in Fig. 3, the upper edge of the back 30 intersects or joins the forward edge of the lid or top 29 in the straight line 60 31, and when said back is viewed at the edge, as in Fig. 2, or in the perspective, it presents a double or reversing curve 32, the general direction of which is the same as the hereinbefore described inclined descending portion 70 9 of the side piece.

The seat is represented at 35, and when viewed from the top or in perspective its inner edge 36 joins the lower edge of the back in a straight line. Said seat is represented 75 as being supported by the middle forwardly extending horizontal portion of the side piece and the lines shown on the surface thereof indicate openings of reticulated work.

I claim—

The design for a desk and seat substantially as herein shown.

In testimony whereof I affix my signature in presence of two witnesses.

JOSIAH C. GOODING.
